UNITED STATES PATENT OFFICE.

CHARLES SNEIDER, OF NEW YORK, N. Y., ASSIGNOR OF TWO-THIRDS TO
SAMUEL L. CLEMENTS AND DANIEL SLOTE, OF SAME PLACE.

FLASK FOR MOLDING METALS.

SPECIFICATION forming part of Letters Patent No. 237,635, dated February 8, 1881.

Application filed December 6, 1880. (No model.)

To all whom it may concern:

Be it known that I, CHARLES SNEIDER, of New York, in the county of New York and in the State of New York, have invented certain new and useful Improvements in Molds for Casting Metals; and I do hereby declare that the following is a full, clear, and exact description thereof, reference being had to the accompanying drawing, and to the letters of reference marked thereon, making a part of this specification.

This invention relates to certain improvements in matrices and molds for casting metals by an improved process for which I have made application for Letters Patent of the United States.

The invention has for its objects to provide a means whereby the air at the face of the matrix may be carried off by the entering metal, and for the escape of the gases developed by the heated metal when poured into the mold, and thus obviate the formation of blow-holes or bubbles and other imperfections in the finished casting, especially at the faces or salient points of the same. These objects I attain by the apparatus more fully hereinafter specified and illustrated in the accompanying drawing, in which is represented a vertical section of a mold for carrying my improvement into effect.

In carrying out my invention I form the matrix or face of the mold of a composition of such nature as to receive the impressions of the pattern, or to have suitable impressions formed therein by cutting, carving, or otherwise, and which will be sufficiently refractory to resist the heat of the fluid metal and form a proper support for the same while cooling. Any substance or compound possessing the above-mentioned requisites may be employed; but for general purposes I have found a composition of the following ingredients, in the proportions named, to answer well, viz: Ground brick or porous clay, one pound; whiting, one-half pound, and plaster-of-paris, one quarter pound, more of the plaster-of-paris being employed in casting the harder metals. This composition I mount on sheets upon a backing of glass or other material that is readily destructible under the influence of an intense heat, and

place such backing and compound in the lower part of a flask filled with sand, with the backing downward, and level off the surface of the sand even with the surface of the matrix which is to form the face of the finished casting. The upper part of the flask is filled with sand in the usual manner, a recess being left to receive the metal forming the body of the casting. At one side, on a line with the face of the matrix, is formed a gate, through which the metal is poured, and at the other side a pool or receptacle, into which the molten metal may escape as it flows over the matrix in the mold, the air and gases at the face of the matrix escaping through the upper part of the pool or receptacle, thus permitting the metal to form and cool on the face of the matrix gradually as the metal is poured into the mold, while the air will be excluded, thus insuring a perfect face to the casting produced. In order to permit the escape of the developed gases the body of the sand below the glass or destructible plates is perforated by means of a suitable instrument in such manner as to form a series of supports or pillars for said glass or plate, and at the same time provide numerous passages for the gas developed by the hot metal, which breaks or destroys the glass or destructible plate sufficiently for the passage of the gases through the same. The said passages may extend partly through the body of sand, as indicated, in which case the gases will be diffused through the sand, or they may extend entirely through the sand, so as to permit the gases to escape directly into the atmosphere.

In the drawings, the letters A A' indicate the upper and lower parts of the flask, respectively, and B the destructible plate, of glass or other material, carrying on its face the matrix C.

D indicates the space between the upper and lower flasks, formed in the sand in which the body of the casting is molded.

E indicates the gate at one side, and F the pool in which the metal collects as it passes over the face of the matrix.

I do not claim in the present case a mold for casting metal constructed with one or more matrices having backings frangible by the

molten metal, and provided with air-passages for the escape of gases, and with a gate or sprue and receptacles for the superfluous metal; neither do I claim the matrix with its frangible backing and the passages in the mold for the escape of gases, as such form the subject-matter of another application for Letters Patent filed by me December 8, 1880.

Having thus fully described my invention, what I claim, and desire to secure by Letters Patent, is—

1. A matrix for casting metals, composed of a facing of refractory material adapted to receive suitable designs and a backing frangible by heat of the molten metal, substantially as and for the purposes specified.

2. A mold constructed as described with a matrix having a backing frangible by the heat of the molten metal, and provided with a pool at one side for the reception of the superfluous metal, and a suitable gate for the introduction of the metal, substantially as specified.

In testimony that I claim the foregoing I have hereunto set my hand this 20th day of November, 1880.

CHAS. SNEIDER.
